Primary Examiner — Catherine S Posthauer*Assistant Examiner* — Joan E. Diehl(74) *Attorney, Agent, or Firm* — Bradley T. Ligibel; Thomas W. Ryan; Clifford R. Lamar, II(57) **CLAIM**

The ornamental design for a blank for a chamfered container as shown and described.

DESCRIPTION

The sole FIGURE is a top plan view of a blank for a chamfered container of the present invention.

The broken lines in the drawing illustrate portions of the blank for a chamfered container that form no part of the claimed design.
